UNITED STATES PATENT OFFICE.

ALBERT C. POWELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 23, 1923. Serial No. 676,478.

To all whom it may concern:

Be it known that I, ALBERT C. POWELL, a citizen of the United States of America, residing at New York city, in the county of Bronx, State of New York, have invented certain new and useful Improvements in Telephone-Exchange Systems, of which the following is a full, clear, concise, and exact description.

10 This invention relates to a telephone exchange system for use between mechanical and manual offices.

The object of this invention is an improved means to connect any line in a full 15 mechanical step-by-step central office to any desired line in a distant manual central office.

In accordance with this invention trunk 20 circuits incoming from the full mechanical step-by-step central office are provided at the manual central office, any one of which may be reached from any line in the full 25 mechanical step-by-step central office by removing the receiver at the station associated with said line and dialing a pre-determined digit or combination of digits known as the office code. The trunk circuit in turn extends the connection to a 30 pre-selected common circuit sometimes known as a recorder and register circuit, and all further selecting signals are recorded in the recorder and register circuit. After all the selecting signals required are 35 received the register circuit proceeds in combination with an indicating device to display the number of the desired called line before an operator in the manual central office, who, thereupon, completes a connection to the called line. Signaling follows 40 automatically and when the called party answers, the talking circuit is automatically established.

A feature of this invention is an improved 45 arrangement whereby a time interval is measured off by the recording device to delay the progress of the call long enough to permit the calling line to dial a party code if required, but permitting the call to proceed immediately after the party code is dialed, or in any event, after the predetermined time interval elapses.

Another feature of this invention is an 50 arrangement providing the operator with a signal in case the complete code of a called 55 number is not dialed together with means

for discharging the recorder, and rendering it available immediately for other calling lines which may be in waiting.

Another feature of this invention is an arrangement hereinafter referred to as the 60 steering relay device whereby the various register switches are connected in proper sequence to the impulse circuit controlled by the calling station.

Another feature of this invention is the 65 lighting of a lamp before the operator should the calling subscriber fail to replace the receiver on the switchhook after a pre-determined time interval has elapsed.

Other features will appear from the detailed description.

Fig. 1 shows a circuit arrangement for providing a disconnect signal to the operator after a suitable delay, when only the called party replaces the receiver upon the 75 substation switchhook after conversation is completed.

Fig. 2 in its upper left-hand corner shows a calling subscriber's station in a full mechanical step-by-step machine switching 80 system; the usual primary and secondary line switches PILS and SLS, a first or office selector S, and a repeater R, all located in the mechanical central office CO; the balance of Fig. 2 and a portion of Fig. 4 show 85 the equipment and circuit arrangement required for the trunk circuit which originates in the full mechanical central office CO (Fig. 2) and terminates in a plug and cord in the manual central office MCO (Fig. 4). In the upper right-hand corner of Fig. 4 is shown a called subscriber's station in the manual central office MCO, accessible to the 90 trunk circuit shown in Figs. 2 and 4. In the lower left-hand corner of Fig. 2 is shown 95 the recorder finder switch having access to the recorder circuit (Fig. 3) and the numerical register switches (Fig. 5). The numerical switches shown in Fig. 5 each have three banks associated with indicating lamps, the horizontal row of banks to which brushes 501, 561, etc. have access being for the home position, the top horizontal row being for the adjacent left position, and the horizontal row to which brushes 502, 100 562, etc. have access being for the adjacent right position. The banks of these three horizontal rows have lamps connected to each terminal thereof for indicating the 105 desired number. For simplification of the 110

100 105 110

drawing, only one lamp has been shown for each register bank of the home position.

The invention is illustrated by the circuits shown in the various figures, 1 to 5, inclusive, arranged in accordance with the key diagram shown in Fig. 6 located in the upper right-hand corner of the first sheet of drawing containing Fig. 1.

In general, the system functions in the following manner: A calling subscriber 200 (Fig. 2) in a full mechanical step-by-step system desiring to communicate with a called subscriber 400 (Fig. 4) in a distant manual central office, removes the receiver 10 from the switchhook at the station 200 and dials the desired number. Removing the receiver causes the primary and secondary line switches PLS and SLS (Fig. 2) to function and extend the calling line to the first or office selector S. The first digit in the series of digits dialed by the calling station 200 is known as a code or office digit and causes the selector S (Fig. 2) to function and extend the calling line to an idle 15 trunk circuit outgoing to the proper manual central office. In circuit with this outgoing trunk circuit at the mechanical central office is a repeater R, for receiving the impulses produced in the calling line circuit 20 by the dial 201 and relaying them over the impulse circuit to a recording device associative with the trunk circuit selected in the distant manual central office. The recording device is equipped with suitable means 25 for receiving the impulses transmitted by the repeater R (Fig. 2), of recording them, and of visibly displaying to the operator at the manual central office by a suitable indicating means (in this case a group of 30 lamps) the number of the desired called line (which we will assume to be the called station 400). The operator at the manual central office then inserts the plug 423 of the trunk cord into the jack 424 of the called 35 line and the called station 400 is automatically signalled. When the called station 40 responds the talking circuit is established and conversation takes place. After the called number has been displayed before the 40 operator in the manual central office, the recording and registering devices (Figs. 3 and 5) which have completed their functions, are released so as to render them available to other trunks in the group if required. 45 To guard against tying up the connection in case the calling party 200 neglects to disconnect, a delay disconnect device (Fig. 1) is provided, which is so arranged that in case the circuit is opened at the called station 400 only, disconnection will not take 50 place immediately; but after the lapse of a predetermined time interval, a signal will be furnished to the operator in the manual central office MCO indicating that a calling station has failed to disconnect and the op-

erator will thereupon proceed to ascertain which connection is affected.

Having described the operation of the system in a general way, it is believed that its operation may be fully understood from 55 the detailed description which follows:

Regular call.

When the receiver is removed at the calling station 200, a circuit is closed, including the calling station and the primary line switch PLS extending the calling line to the secondary line switch SLS which in turn operates and extends the calling line to the first or office selector circuit S. The dial 201 is now operated and released and the selector S functions to select an idle trunk in the group of trunks outgoing to the distant manual central office MCO (Fig. 4). We will assume that the trunk shown in part in Fig. 2 is the one selected, in which case the calling line 200 is extended to the repeater R which operates and closes a bridge across the conductors 202 and 203 to operate the impulse relay A as follows: battery, left hand winding of relay A, 204, 205, 258, 202, bridge circuit repeater R, 203, 259, 208, 209 to ground at the right winding of relay A. The windings 206 and 207 of the repeating coil are short-circuited at this time to prevent distortion of the impulses transmitted over the line to operate the impulse relay A, herein-after fully described. The relay SLO operates over an obvious circuit to ground at 100 the armature 229 of the relay A. Relay CI-1 operates as follows: battery, winding of the stepper 210, 211, winding of relay CI-1, 212, 213, 214, 215, 216, 217 to ground. The stepper 210 does not operate due to the high 105 resistance of the relay CI-1 in series with it. Relays CI-2 (Fig. 2) and HLD (Fig. 3) operate in series as follows: battery, winding of relay HLD (Fig. 3) 332, 232, brush 222, winding of relay CI-2 to ground at 110 219. Relay GRD (Fig. 3) operates over an obvious circuit under control of the relay HLD. Relay CI-2, in operating, opens at 240 the lead to the relay T individual to the trunk circuit and connects ground at its armature 240 to the corresponding multiple terminals of all other recorder finder switches by way of brush 220 and lead 230. Lead 230 is multiplied to the corresponding 115 terminal of all other switches in the group, hence, when any terminal, for example 250, is grounded the ground is connected to every corresponding multiple terminal of other switches in the group. 120

The recorder finder switches (Fig. 2) are arranged to preselect an idle recorder circuit, hence, all other recorder finder switches which may be resting upon the multiple terminals of this recorder finder in the proper multiple arcs of other similar 130

switches must now be stepped to the terminals associated with the next idle recorder circuit. This is accomplished as follows: There is a relay T (Fig. 2) individual to each trunk circuit and whenever any trunk circuit is not in use, the corresponding relay TR-2 connects battery at the contact corresponding to 218 through the winding of its T relay to the lead 230, which is common to the multiple arcs of all the recorder finder switches, by way of all the parallel circuits corresponding to 218, winding of relay T, 240 and brush 220. Assuming that the brush of one or more other recorder finder switches corresponding to the brush 220 is resting upon the terminal corresponding to terminal 250 of the recorder finder switch multiple bank, parallel circuits through all the relays T will be connected by way of common lead 230, terminal 250, brush 220 to ground at contact 240 of the relay CI-2 (Fig. 2). The various relays T will operate and close obvious local circuits to operate the various associated stepper magnets similar to 210 (Fig. 2), and in releasing will step their recorder finder switch brushes to the terminals of the next recorder circuit in the group. Whenever the recorder finder switch brushes come to rest upon the test terminal of an idle recorder circuit the ground to hold the relays T operated, will be opened and these relays will release, preventing the associated stepping magnets from rotating the switch brushes any further until the seizure of another trunk circuit necessitates a recurrence of this cycle of operations.

The operation of relays CI-1 and CI-2 extend the leads 231, 233, 234, and 235 by way of brushes 221, 223, 224 and 225 for purposes which will hereinafter be made apparent.

It has been observed that the recorder circuit (Fig. 3) is made busy (ground at 240) when the relay CI-2 operates. This immediate busy condition is intended to prevent the possibility of a double seizure of a recorder between the time the brushes come to rest upon the terminal group of a particular recorder, and the time required to operate relay GRD (Fig. 3), which supplies at 330 the ground intended to make the recorder circuit test busy to all other recorder finder switches, (except the one in Fig. 2 to which it is connected) until the recorder circuit has completed all its functions as hereinafter described.

Dialing.

The recorder circuit is now ready to receive the thousands series of impulses produced by the dial 201 at the calling station 200. The dial 201 is operated and released and as it returns to normal it interrupts the circuit including the calling station loop and the repeater R, which in turn interrupts the

circuit including the repeater R and the relay A. Relay A which is a fast relay, is designed to follow the impulses reproduced by the repeater R. The impulsive circuit to operate the stepper switch 515 (Fig. 5) which responds to the first numerical or thousands digit of the dialed number, is as follows: ground, armature 229 of relay A, 236, 237, 238, 239, 246, 446, 447, 448, 449, 257, 241, brush 221, 231, 331, 304, 305, 306, 307, 308, 309, 310, 311, 312, 513, 514, 515, 516, 517, 318, winding of relay ADV to battery at 319. The relay B (Fig. 3) is connected at 313 to the lead 305 which results in the relay B being in parallel with the step- 80 per 515.

Relay B also operates and closes an auxiliary or booster circuit to insure the proper operation of the stepper 515 as follows: ground, armature 320 of relay HLD, 321, 322, 323, 324, 325, 326, 327, 328, 532, 515, 516, 517, 318, winding of relay ADV to battery at 319. The stepper 515 and relay ADV operate in series. Stepper 515, in operating, opens its operating circuit at its armature 514, but the stepper does not release because the booster circuit is still closed at relay B. When the impulse relay A re-operates, relay B releases, opening the booster circuit through stepper 515 which now releases and, 90 on its backward stroke, rotates the brushes 500 to 505, inclusive, one step in a counter clockwise direction to the terminal 506 and the corresponding terminals of the other arcs of the same switch. With brush 505 resting upon terminal 506 a circuit is closed through the relay ST-1 (Fig. 3) as follows: ground, armature 320, relay HLD (Fig. 3) 321, 314, 315, 316, 317, winding of relay ST-1, 329, 336, 536, 505, 506, 537, 337, 338 to battery at 339. Relay ST-1 will not operate at this time as it is shunted by a path through the low resistance 340 to ground at armature 341 of relay ADV. 95 100 105

Relay B and stepper 515 follow the impulses produced by the impulse relay A (Fig. 2) and relays SLO (Fig. 2) and ADV (Fig. 3) which are slow to release, remain operated throughout the thousands impulse train. The stepper 515 rotates one step per 415 impulse until the train of impulses produced by relay A cease.

After the last impulse of the thousands digit train of impulses ceases, relay ADV (Fig. 3) releases, removing at 341 the low 120 resistance shunt 340 from around the relay ST-1 which now operates and locks in an obvious local circuit. With the relay ST-1 operated, the impulsive and booster circuits are transferred at its armatures 311 125 and 327, respectively, from the stepper 515 of the thousands register switch, to the stepper 525 associated with the hundreds register switch.

The digit corresponding to the hundreds 130

digit of the desired number is now dialed at station 200 and the stepper 525 operates and rotates the hundreds register switch which takes the proper setting in the same 5 general manner as the thousands register switch. At the end of the impulse train, relay ST-2 operates and locks in the same general manner as relay ST-1, and transfers the impulsing and booster circuits at its 10 armatures 310 and 326 respectively to the stepper 535 of the tens digit register switch. In like manner the tens digit is registered and relay ST-3 operates and locks and transfers the impulsing and booster circuits 15 at its armatures 309 and 325 respectively to the stepper 545 of the units register switch. After units registration is completed, relay ST-4 operates to transfer the impulsing and booster circuits at its armatures 307 and 20 respectively, to the stepper 555 of the stations register switch.

It is necessary to delay the displaying of the called number on the indicating device until the calling party at station 200 has 25 had sufficient time to dial the party code of the called station where a party code is required, and this is accomplished by using a display delay device in the manner herein-after described. The relay ST-4, which 30 operated after units registration was completed, connects the interrupter 342 to the relay BB by way of 343 and 344, and the relay BB operates and releases under control of the interrupter 342. Each time relay BB operates ground is connected to lead 345.

Operation of timing relays.

First stage.—When the first ground impulse is connected to lead 345 by relay BB, the relay W operates as follows: battery, left winding relay Z, winding relay W, 346, to ground at 345. The relay Z which is in series with the relay W is marginal and 45 will not operate under this circuit condition. The operation of relay W connects the ground by way of 349, 350 and 351 to the right winding of relay Z which is thereby connected in series with its left winding 50 and the winding of relay W. No change is effected in the circuit, however, due to the short-circuiting of the right winding of relay Z by the ground at relay BB by way of 346 and 345.

Second stage.—When relay BB releases removing ground from lead 345, relay Z operates as follows: battery, left winding of relay Z, winding relay W, right winding of relay Z, 349, 350 to ground at 351.

Third stage.—When relay BB reoperates the relay W is short-circuited by ground on lead 345, causing the relay to release, but relay Z holds to the same ground by way of 347 and 345. The relay W1 now 65 operates as follows: battery, left winding

relay Z1, winding relay W1, 352, 354, 348, 350, to ground at 351. Relay Z1 is so designed that it will not operate under this circuit condition.

Fourth stage.—When relay BB releases 70 removing ground from lead 345, the holding circuit through the left winding of relay Z is opened and relay Z releases, removing the short circuit from the right winding of relay Z1, which operates over the following 75 circuit: battery, left winding relay Z1, winding relay W1, right winding relay Z1, 355, 350, to ground at 351.

These four stages constitute a complete 80 cycle of operations of the relays Z1 and W. It is evident that relays Z1 and W1 will remain operated over the circuit last described, until solid ground is again connected to 353, by way of 354 and 348. This 85 cannot occur until the third stage of the cycle is again reached when relay Z will be operated and relay W released, releasing relay W1 and operating relay W2.

During the fourth stage of the second 90 cycle, relay Z2 operates and locks to ground in series with relay W2. Relay Z2, however, will not release during subsequent changes in the condition of any of other five 95 relays in the combination. This is because when relay W2 is operated, relays Z2 and W2 lock in series by way of 356 and 357 to ground at 350, and when relay W2 is normal, relay Z2 is locked over the circuit by way of 358, 359, 391 and 350, to ground at 351.

The relay BB continues to function under control of interrupter 342, and the Z, W, Z1, W1 and W2 relays will continue to operate and release in accordance with the following table: (It will be remembered that during 100 the fourth stage of the second cycle, relays W2 and Z2 are operated.)

Third cycle.

First stage.—Relay W operates; relays 110 W2 and Z2 hold.

Second stage.—Relay Z operates; relays W, W2 and Z2 hold.

Third stage.—Relay W releases; relay W1 operates; relay Z, W2 and Z2 hold.

Fourth stage.—Relay Z releases; relay 115 Z1 operates; relays W1, W2 and Z2 hold.

Fourth cycle.

First stage.—Relay W operates; relays 120 W1, Z1, W2 and Z2 hold.

Second stage.—Relay Z operates; relays W, W1, Z1, W2 and Z2 hold.

Third stage.—Relays W, W1 and W2 release; relays Z, Z1 and Z2 hold.

Fourth stage.—Relays Z and Z1 release; 125 relay Z2 holds.

Fifth cycle.

First stage.—Relay W operates; relay Z2 130 holds.

Second stage.—Relay Z operates; relays W and Z2 hold.

Third stage.—Relay W releases; relay W1 operates; relays Z and Z2 hold.

Fourth stage.—Relay Z releases; relay Z1 operates; relays W1 and Z2 hold.

Sixth cycle.

First stage.—Relay W operates; relays W1, Z1 and Z2 hold.

Second stage.—Relay Z operates; relays W, W1, Z1 and Z2 hold.

Third stage.—Relays W and W1 release; relays Z, Z1 and Z2 hold.

It is thus evident that during the third stage of the sixth cycle, the same relays (Z, Z1 and Z2) are operated as during the third stage of the fourth cycle.

As long as relay Z2 is locked by way of 350 to ground at 351, the relays will repeat the operations from the third stage of the fourth cycle to the third stage of the sixth cycle. Hence, the maximum number of combinations obtainable is represented by the table from the first stage of the first cycle to the second stage of the sixth cycle, or a total of twenty-two stages.

If we regard each make and break of interrupter 342 (or two of the stages) as one unit, we have a total of eleven units in which we may delay the further advance of the call after units registration, in order to allow the calling station 200 to dial the station code, if required.

If the interrupter 342 has a make period of .5 seconds, and a break period of .5 seconds, the delay interval will be a maximum of eleven seconds. If the interrupter 342 has a make period of .3 seconds and a break period of .2 seconds, the delay interval will be a maximum of five and one-half seconds.

Any other desired delay may be obtained by varying the number of impulses per second produced by interrupter 342, by inserting additional Z and W relays in the circuit, or by changing the wiring of leads 360 and 361 at the contacts of the relays Z and W, etc.

Let us assume that leads 360 and 361 are closed when relays Z1 and Z2 are operated, as shown by the wiring in Fig. 3, then the leads 360 and 361 will be connected together in the fourth stage of the third cycle or after an interval of six units, and assuming interrupter 342 has .3 seconds make and .2 seconds break, the delay after units registration will be a maximum of three seconds, which ordinarily affords ample time to the calling station to dial the station code, where required.

No stations pulses.

Assuming stations pulses are not required, the LP relay (Fig. 3) will operate after the

proper delay as follows: battery, winding relay LP, 362, 360, 363, 364, 365, 366, 361, 507, 508, brush 594, 509, 510, 367, 368, to ground at 341 of relay ADV. Relay LP locks as follows: battery, winding of relay LP, 315, 314, 321, to ground at 320 of relay HLD.

65

70

Stations pulses.

Assuming, however, that stations pulses are required, then stepper 555 will be energized over the impulsing circuit previously traced by way of 307 and 324 of relay ST-4 (Fig. 3). The stepper 555 will set the register brushes 590 to 595, inclusive, in accordance with the number of impulses received over the impulse circuit from the impulse relay A, (Fig. 2). When relay ADV releases at the end of the stations series of impulses, a circuit to operate relay LP is closed as follows: battery, winding relay LP, 362, 369, 511, 512, brush 594 (off normal), 509, 510, 367, 368, to ground at 341 of relay ADV. Relay LP locks in the manner previously described.

75

80

85

90

Thus, it will be seen that in either case the relay LP is operated under control of relay ADV in order to advance the progress of the call.

The operation of relay LP opens at 315 the holding circuit for relays ST-1 and ST-2 which release and relay ST-1, in releasing, opens at its armature 370 the locking circuit for relays ST-3 and ST-4 which release. The release of relay ST-3 opens at 351 the locking circuit for the Z and W timing relays which also release, and the release of relay ST-4 opens the circuit including the impulsing 342 and the relay BB.

95

The assignment lamp 401, (Fig. 4) now lights over the following circuit: battery, relay LP, 371, resistance 372, 333, 233, brush 223, 243, 252, 476, lamp 401 to ground at 403.

100

105

Displaying the called number.

The display key DK (Fig. 2) is depressed, and relays K and PC operate in series as follows: battery, winding relay CON (Fig. 4), winding relay PC, right winding relay K, 404, 253, 254, 255, 256, 405, 406, 407, 408, 409, 257, 216, to ground at 217 of relay SLO. Relay L operates under control of relay PC and locks in series with the peg count register MR. The register MR operates and registers the call, and short-circuits the relay L which releases. The register MR remains locked until the relay PC releases. The relay K, operated, locks as follows: battery, winding relay CON, winding relay PC, windings relay K, 410, 411, 412, 406, 407, 408, 409, 257, 216, to ground at 217 of relay SLO. The relay K1 operates over an obvious circuit under control of relay K.

110

115

120

125

Relays MG and SNR (Fig. 3) operate under control of relay K over the following

circuit: battery, winding relay MG, winding relay SNR, 335, 235, brush 225, 245, 248, 413, to ground at armature 414 of relay K.

The home lamps control relay HL, and relay REL, (Fig. 3), operate in parallel over an obvious circuit under control of relay MG, and relay HL connects ground at 373 to 377, inclusive, to the brushes 501, 561, 571, 581, and 591, respectively, of the numerical register switches Fig. 5. Each lead in each arc associated with each of the brushes aforesaid, is connected to a lamp such as lamps 550 to 554, inclusive or other suitable number indicating device. Hence, circuits from battery through the proper lamp by way of the brushes are closed to ground at relay HL displaying before the operator in the manual central office MCO (Fig. 4) the number of the desired line and the proper party code. Relay REL operated, short circuits the resistance 302 and causes lamp 300 of the register circuit to glow brightly as an indication that the call is progressing properly.

The form and type of the number indicating device used is not material to this invention. The device may be in any form, a suitable one being described in Automatic Telephony by Smith and Campbell, second edition, page 240, and shown therein at page 250, Fig. 217.

Before inserting the plug 423 in the jack 424 of the called line, we will discuss the further setting of various relays, particularly the ringing relays RP and RV (under control of the register switches).

The circuit through the assignment lamp 401 is opened at 403 by the operation of relay K1, thus extinguishing the lamp.

Relays TR1 and TR2, which are in parallel, now operate over an obvious circuit to ground at 416 of relay K1. Relay TR1 locks by way of 249 under control of relay SLO, removes at 258 and 259 the short circuit from around windings 206 and 207, respectively, of the repeating coil (it will be recalled that windings 206 and 207 were short circuited during the dialing period to prevent distortion of the impulses transmitted to the impulse relay A). Relay TR2 is held operated under control of relay TR1, opens at 236 the impulse circuit controlled by impulse relay A, at 218 the battery feeder to relay T, and at 213 the operating circuit for relay CI-1. Relay CI-1 does not release, because a substitute holding circuit was provided by the operation of relay K1 as follows: battery, stepper 210, 211, winding relay CI-1, 260, 419, 417, 418, 420, 261, 215, 216, to ground at 217 of relay SLO.

The operation of relay K connected the relay RP to the register circuit by way of 427, 448, and brush 221 of the recorder

finder switch; likewise, the operation of relay K1 connected relay RV to the register circuit by way of 415 and brush 224 of the same switch. Relays RV, RP and PU control the type of signaling current supplied to the called station and the station signalled on a party line will depend upon the operated or normal condition of these relays.

For purposes of illustration, let us assume that party: W is signalled by applying battery of negative polarity superimposed with alternating current to the ring conductor 421 of the called line 400. M is signalled by applying battery of negative polarity superimposed with alternating current to the tip conductor 422 of the called line 400. R is signalled by applying battery of positive polarity superimposed with alternating current to the ring conductor 421 of the called line 400. J is signalled by applying battery of positive polarity superimposed with alternating current to the tip conductor 422 of the called line 400.

To signal the various parties, it will be necessary to operate relays PU, RP and RV according to the following table:

W, RP and RV normal.

M, PU and RV operated RP normal.

R, RP operated PU and RV normal.

J, PU, RP and RV operated.

If the calling station 200 desires to call the party J the digit 5 corresponding to the code letter J would be dialed; similarly for M the digit 6, for R the digit 7 and for W the digit 9.

The stepper 555 (Fig. 5) would rotate and step the brushes 590 to 595, five, six, seven or nine steps to the corresponding terminals of the stations register arcs. For J this would be five steps or terminal 518 of the arc associated with brush 595, for M six steps or terminal 519, for R seven steps or terminal 520, and for W nine steps or terminal 521.

Assuming the stations register is set for party W, then brush 595 will be resting on terminal 521 and no circuit will be closed. Hence, relays RP and RV remain normal.

Assuming, however, that party M is required, then with brush 595 resting on terminal 519, a circuit to operate relay RV (Fig. 2) will be closed as follows: battery, winding relay RV, 262, 425, 415, 426, 263, 264, 265, 244, brush 224, 234, 334, 522, 519, brush 595, 523, 380, to ground at 381 of relay REL.

Assuming party R is required, then with brush 595 resting on terminal 520, a circuit to operate relay RP (Fig. 4) is closed as follows: battery, winding relay RP, 427, 448, 449, 251, 241, brush 221, 231, 331, 383, 524, 520, brush 595, 523, 380 to ground at 381 of relay REL.

Assuming party J is required, then with

- brush 595 resting on terminal 518, a circuit to operate the relay OPV (Fig. 3) will be closed as follows: battery, winding relay OPV, 384, 526, 518, brush 595, 523, 380, to ground at 381 of relay REL. Relay OVP operated, connects ground at 379 to lead 331 to operate relay RP and at 378 to lead 334 to operate relay RV. Relay RP, if operated locks over an obvious circuit to ground at 217 of relay SLO. Likewise, relay RV if operated, locks over an obvious circuit to the same ground.

Completing the connection.

- 15 When the plug 423 of the trunk (Figs. 3 and 4) is inserted in the jack 424 of the called line 400, relay SL (Fig. 4) operates over the sleeve in series with relay CO to ground. The holding circuit for relay K is opened at 407 and 408 of relay SL and relay K releases, in turn releasing relay K1 (Fig. 4) and relays SNR and MG (Fig. 3). The holding circuit for relay CI-1 is opened at 417 and 418 by the release of relay K1, and relay CI-1 releases releasing relay CI-2. Relays CI-1 and CI-2 open the various circuits over brushes 220 to 225, inclusive, previously described, releasing the recorder and register for service, if required by some other stations trunk.

We will delay a discussion of the return to normal of the recorder and register circuits until after the call has been completed to station 400.

- 35 Relay SL operates relay R2 in parallel with the disconnect lamp 428 as follows: (path 1) battery, 429, lamp 428, 430, 431 to ground at 432, (path 2) battery, 429, 433, 266, 267, 268, 269, 434, 489, winding relay 40 R2, 490, 491, 479, 493, 492, 431, to ground at 432. The lamp 428 will not glow due to the low resistance winding of relay R2 in parallel with it.

Signaling the called party.

- The pick-up relay PU operates when the interrupter 435 connects battery to lamp 436 for a brief interval before the commencement of the machine ringing cycle. Machine ringing and the function of the pick-up relay are so well known in the art that it is not proposed to explain the operation of this portion of the system in any detail.

- To ring party W (relays RP and RV normal) the circuit would be as follows: signaling current from the ringing machine to 441 and right winding relay TRPG, 443, 444, 445, 270, 271, 272, 273, 450, 451, 452, 453, 454, 455, 421, 456 to ground at ring- 60 er 457.

- To ring party M (relays PU and RV operated) the circuit would be as follows: signaling current 441, right winding of relay TRPG, 443, 444, 458, 488, 487, 486, 274, 275, 276, 277, 459, 460, 461, 462, 463, 464, 465, 466, tip conductor 422, to ground through the condenser and ringer in series at station M (not shown).

466, tip conductor 422, to ground through the condenser and ringer in series at station M (not shown).

To ring party R (relay RP operated and relay RV normal) the circuit would be as follows: signaling current 442 and left winding of relay TRPG, 494, 468, 469, 444, 445, 270, 271, 272, 273, 450, 451, 452, 453, 454, 455, ring conductor 421 to ground through the condenser and ringer in series at station R (not shown).

To ring party J (relays PU, RP and RV operated) the circuit would be as follows: signaling current 442 and left winding of relay TRPG, 494, 468, 469, 444, 458, 488, 487, 486, 274, 275, 276, 277, 459, 460, 461, 462, 463, 464, 465, 466, tip conductor 422 to ground through the condenser and ringer in series at station J (not shown).

A single party line will be signalled in the same manner as the W party in a multi-party line.

During the signaling period, ground will be connected to the line conductor which is not connected to the source of signaling current at one of the contacts 278 or 279 of the relay RV. One reason for this is to prevent the false signaling of parties on the opposite side of the line at the moment the receiver is removed from the switchhook at the called station. The ground at 278 or 279 operates to short circuit the ringers on the opposite side of the line to accomplish this object. Another reason for this is to supply a ground return during signaling on a single party line.

During the signaling period, part of the ringing current flows through one of the condensers 470 or 471 and one of the windings 279 or 282 of the repeating coil (Fig. 2) inducing alternating current in one of the associated windings 206 or 207 of the repeating coil, thereby transmitting alternating current back over the trunk to the calling station 200, which furnishes a tone in the receiver 283 as an audible indication that the ringing current is connected to the called line.

The called station will be signalled and the receiver 467 will be removed from the switchhook. The relay TRPG is designed to be slow to operate so that it will not open its contacts 493 and 479 during signaling, but the moment the receiver 467 is removed

from the switchhook the impedance of the signaling circuit including relay TRPG is reduced so as to allow the relay to operate and separate its armature 479 and back contact 493, thus removing the short circuit from the winding of relay R3 which operates in series with relay R2, short circuiting the latter at 480 and 490 and causing its release. The effect of this operation is to substitute the relay R3 for the relay R2 previously in parallel with the disconnect lamp

428. During this substitution the lamp 428 remains extinguished.

The release of relay R2 disconnects at 452 and 461 the ringing current from the trunk and called line and opens at 481 the circuit through the relay PU which releases. The circuit through relay TRPG is opened releasing the relay. A circuit is now established from the called line to operate relay 10 S1 (Fig. 2) as follows: battery, 278, winding 299 of the repeating coil, winding relay S1, 280, 482, 483, 452, 453, 454, 455, 421, station 400, 422, 466, 465, 464, 463, 462, 461, 472, 473, 281, to ground at 282. The S2 relay 15 now operates under control of relays S1, TR1 and SLO. Relay S2 reverses the direction of the current flowing in the trunk conductors and the repeater R to operate a call charging device (not shown) associated with 20 the calling line 200.

The stations 200 and 400 are now connected together and conversation takes place.

Discharging the recorder circuit and the register switches.

25 After the called number was displayed upon the indicator, the ringing combination set and the plug inserted in the jack of the called line, the recorder circuit and the register switches (Figs. 3 and 5) were no longer required, hence, the SNR and MG relays (Fig. 3) released upon the release of relay K and the CI-1 relay (Fig. 2) and LP relay (Fig. 3) released upon the release of relay 30 K1. The release of the relays SNR MG releases relays HL and REL (Fig. 3). The release of the former extinguishes the display on the indicator before the operator, and of the latter extinguishes lamp 300, and 35 releases relay OPV (if operated).

The release of relay CI-1, released the relay CI-2 (Fig. 2) and relay HLD (Fig. 3) which were in series. The release of relay HLD opens the circuit of relay GRD, but 40 the latter remains operated over leads 385 and 527 to ground at brushes 503, 563, 573, 583, and 593, which are off normal. Hence, as long as any one of the register switches are off normal the relay GRD remains operated, holding the recorder circuit busy to 45 all other trunks until relay GRD releases as hereinafter described.

The release of relay HLD operates relay RES (Fig. 3) over an obvious circuit controlled by the relay GRD.

55 Stepper 555 now operates to restore the stations register switch to normal over a circuit as follows: battery, 319, winding relay ADV, 318, 517, 516, stepper 555, 528, 529, 530, 386, 387, 388, 389, 531, brush 594 (off normal) 509, 510, 367 to ground at 321 of relay HLD.

60 With the stations switch in normal position, a circuit similar to the one traced for 65 the station switch, is closed by way of brush

584, and one of the terminals 531 or 508 of the stations register switch are to operate the units register stepper 545.

In like manner each of the steppers 535, 525 and 515 operate in sequence to restore 70 their respective register switches to normal. With all the register switches in the normal position relay GRD releases, releasing relay RES and restoring the recording circuit and register switch to normal. 75

Disconnection.

Calling party disconnects first.—When the receiver 283 is replaced on the switchhook 247 at station 200, a circuit including the 80 repeater R (Fig. 2) is opened, causing the repeater to restore to normal and open the holding circuits for the primary line switch PLS, the secondary line switch SLS and selector S, which also restore to normal. 85

When the repeater R releases, the circuit including the repeater R and the impulse relay A is opened causing the relay A to release. The circuit through the relay SLO is opened by the release of relay A releasing 90 relay SLO. The release of relay SLO opens at its contact 217 the holding circuits for relays TR1, TR2, S-2, RV and RP, releasing these relays.

The release of relay TR1 removes the 95 shunt formed by the winding of relay R3 from around the disconnect lamp 428 releasing relay R3 and lighting the lamp 428 as a disconnect signal to the operator in the manual central office MCO. When the plug 100 423 is removed from jack 424, relays S1 and SL release, the disconnect lamp 428 is extinguished and the circuit is restored to normal.

Called party disconnects first.—When the receiver 467 is replaced on the switchhook at station 400, a circuit including relay S1 is opened at the switchhook contacts releasing relay S1 which in turn releases relay S2. 105

A circuit is now closed to operate relay ST 110 (Fig. 1) as follows: battery, winding relay ST, 100, 284, 285, 286, 287, 484, 485, 474, 475, 476, lamp 401 to ground at 403 of relay K1. The lamp 401 will not light due to the high resistance of relay ST in series with it. 115

The operation of relay ST closes an obvious circuit to operate relay CT. The interrupter 103 is now connected to the relay INT by way of 104 and 105. Relay INT operates, connecting ground intermittently 120 to lead 108 by way of 106 and 107.

The timing relays W3 and Z3 to W7 and Z7 operate in the same general manner as the timing relays W and Z to W2, Z2 (Fig. 125 3) except that relay Z7 does not lock up permanently in the same manner as relay Z2.

When relay Z7 is operated and relay W7 is normal, a circuit is closed to operate relay PS by way of lead 102 to ground at armature 101 of relay CT. 130

The relay CA operates over an obvious circuit including contact 112 of relay PS. When the timing relays release, relay PS also releases, allowing relay CB to operate in series with relay CA, thus connecting relay CC by way of lead 111 to the contact 112 of relay PS. The timing relays Z3, W3 to Z7, W7, reoperate, under control of interrupter 103, and relay PS operates in the manner previously described. When relay PS reoperates at the completion of the second cycle of operations of the timing relays, relay CC operates as follows: battery, relay PS, 112, 111, 113, 114, 115, 116, winding relay CC to ground. Relay CC locks under control of relay CB by way of 116, 117, 118 and 119. The lamp 120 (Fig. 1) located in the switchboard before the operator in the manual central office MCO (Fig. 4) lights over an obvious circuit as an indication to the operator that one of the trunk circuits in her position has been held for an unreasonable length of time after the called party has disconnected.

The lamp 120 is common to all the trunks in the position and in order to ascertain the particular trunk in the position which is effected, the operator depresses the flashing key FK (Fig. 1) thereby shunting the relay ST by the resistance 110. The resistance of the parallel combination of the winding of the relay ST and the resistance 110 is such as to permit the assignment lamp 401 (Fig. 4) to light as an indication that this trunk is the one which has been held up for an improper length of time.

The operator now removes the plug 423 from the jack 424 and inserts it in a jack associated with the circuit of a supervising operator, who challenges on the trunk to ascertain whether or not station 200 is still on the line.

Incompleted calls.

Should the station 200 originate a call and operate the dial for one or more digits, but fail for any reason to dial a sufficient number of digits, to set the thousands, hundreds, tens and units register switches (Fig. 5) the call will not progress and the lamp 300 (Fig. 3) will remain lighted dimly for an undue length of time. The attendant will observe this and depress the incomplete display key IDK (Fig. 3). This will light the assignment lamp 401 as follows: battery, key IDK, resistance 372, 333, 233, brush 223, 243, 252, 402, 476, assignment lamp 401, to ground at contact 403 of relay K1. The operator at the manual central office MCO (Fig. 4) will operate the display key DK (Fig. 3) operating the relay K in the usual manner. Relays K1, MG, SNR, REL and HL will operate in the manner previously described and those digits which have been dialed will be dis-

played on the indicator before the manual operator.

The plug 423 will then be inserted in the jack of the line connected to a supervising operator who will inform the calling subscriber that he has failed to dial properly and request him to disconnect and originate another call.

All recorders busy.

If all the recorders (Figs. 3 and 5) are busy at the time the trunk is seized by the repeater R, the CI-1 and CI-2 relays will not operate.

When the subscriber at the calling station 200 starts to dial, the impulse relay A releases, operating relay MC as follows: battery, windings relay MC in series, 288, 289, 238, 237, 236, to ground at armature 229 of the impulse relay A. The relay MC locks by way of 290 and 216 to ground at 217 of relay SLO. Relays TR-1 and TR-2 operate in parallel as follows: battery, windings TR-1 and TR-2 in parallel, 291, 292, 293, 294, 256, 405, 406, 407, 408, 409, 257, 216, ground at 217 of relay SLO. The disconnect lamp 428 (Fig. 4) now lights over a circuit as follows: battery, resistance 429, lamp 428, 430, 477, 478, 295, 296, 297 to ground at 298. The operator at the manual central office MCO will connect the trunk to a supervising operator who will determine the number of the desired called line.

The proper signaling current will be applied to the line by operating one of the keys J, M, R or W (Fig. 2) which will operate the relays RP or RV, or both, as the case may be, in the same general manner and with the same general results as in a regular call by way of the recorder and register circuits. After removing the plug 423 of the trunk from the jack associated with the supervising operator the display key DK is depressed and relays K and K1 operate and lock as in a regular call.

The plug 423 will then be inserted in the jack of the desired line and the call will progress in the usual way.

Whenever all recorder circuits in the group are busy the brushes of any idle recorder finder will advance until they rest upon the terminal corresponding to the terminal 242 of all other recorder finder switches. The terminal 242 which is connected to the lead 226 is multiplied to the terminal of all other recorder finder switches corresponding to the terminal 242. Lead 226 is also multiplied to the contact 390 of the relays GRD associated with all the recording circuits in the group. As long as the recording circuits are busy all the relays GRD will be operated and the common lead 226 will be free from ground. Whenever any recorder circuit becomes idle its relay GRD will release, connecting ground to 130

terminal 242 by way of lead 226 and contact 390. The relays T individual to the various idle trunks will now operate in parallel over a circuit as follows: battery at 5 relay TR2, 218, winding relay T, 240, brush 220, terminal 242, common lead 226 to ground at 390 of relay GRD. The various relays T will operate and close the circuit to the various steppers similar to 210 which 10 will operate, open their operating circuit and release, and in so doing step the brushes of their respective switches to the terminals corresponding to terminal 227, thence to the terminal corresponding to terminal 228 in the same manner. In this way 15 the various recorder finder switches individual to the various trunks in the trunk group are at all times resting upon a pre-selected idle recorder circuit if an idle circuit is available or if all recorder circuits 20 are busy are resting upon a particular terminal of the switch arc, where they will remain until a recorder circuit becomes idle when they will again proceed to preselect 25 the idle recorder circuit.

It should be understood that the number of line switches may be increased or reduced as desired without departing from the spirit of the invention.

30 It should also be understood that the number of selector switches introduced between the calling subscriber and the trunk circuit may be varied as desired without in any way departing from the spirit of the 35 invention.

It should also be understood that the trunk repeater may be entirely omitted or additional trunk repeaters inserted as required without in any way departing from the 40 spirit of the invention.

What is claimed is:

1. A telephone system comprising a calling line, an impulse sender, an impulse relay, a circuit including the calling line and 45 the impulse relay controlled by the impulse sender, a plurality of selector switches operable in sequence, a slow relay, an impulse circuit including one of the selector switches and the slow relay controlled by the impulse 50 relay for setting the selector switch and operating the slow relay, means controlled by the joint action of the slow relay and of each selector switch in sequence excepting 55 the last, for substituting the next succeeding selector switch in the sequence for the prior selector switch at the end of the corresponding impulse train until all the required selector switches in the train have been properly set, means for indicating the progress 60 of a call, manually controlled means for releasing the selector switches, a called line, manually controlled means for linking the calling and called lines together, and signaling means for summoning the called line. 65

2. A signaling system comprising an im-

pulser, a train of timing relays, a circuit including the impulser and the relays in succession whereby the relays measure off substantially uniform time intervals, means for locking the last relay in the train thereby 70 permitting the other timing relays to continue to measure off additional time intervals until all the relays in the train are again operated in succession, a timed device, and a circuit controlled by one or more of the 75 timing relays in combination for functioning the timed device.

3. In a telephone system, an operator's position, a plurality of lines terminating at said position, the numbers of which include 80 a variable number of digits, a register set comprising sufficient registers to register the number of a called one of said lines containing the maximum number of digits, means controlled by said registers for indicating to the operator any registered number, and a train of counting relays operable to delay the operation of said means until sufficient time has elapsed to enable the maximum 85 number of digits in any number to be registered.

4. In a telephone system, an operator's position, a plurality of lines terminating at said position the numbers of which include 90 a variable number of digits, a register set comprising sufficient registers to register the number of a called one of said lines containing the maximum number of digits, means for setting said registers in succession, means controlled by said registers for 95 indicating to the operator any registered number, a train of counting relays operable to delay the operation of said last means until sufficient time has elapsed to enable the maximum 100 number of digits in any number to be registered, and means operable following the setting of an intermediate one of said registers for initiating the operation of said relays.

5. In a telephone system, an operator's 110 position, a plurality of lines terminating at said position, the numbers of which include a variable number of digits, a register set comprising sufficient registers to register the number of a called one of said lines containing the maximum number of digits, means for setting said registers in succession, means controlled by said registers for indicating to the operator any registered 115 number, means operable following the setting of the last one of said registers for controlling said indicating means, a train of counting relays operable to delay the operation of said last means until sufficient time has elapsed to enable the maximum number 120 of digits in any number to be registered, and means operable following the setting of an intermediate one of said registers for initiating the operation of said relays.

6. In a telephone system, an operator's po- 130

sition, a plurality of lines terminating at said position, the numbers of which include a variable number of digits, a register set comprising sufficient registers to register the 5 number of a called one of said lines containing the maximum number of digits, means controlled by said registers for indicating to the operator any registered number, a signal for apprising the operator when a number 10 is fully registered, a timing mechanism operable to delay the operation of said signal until sufficient time has elapsed to enable the maximum number of digits in any number to be registered, and operator controlled means for operating said indicating 15 means.

7. In a telephone system, an operator's position, a plurality of lines terminating at said position, the numbers of which include 20 a variable number of digits, a register set comprising sufficient registers to register the number of a called one of said lines containing the maximum number of digits, means controlled by said registers for indicating to 25 the operator any registered number, a lamp for apprising the operator when a number is fully registered, a train of counting relays operable to delay the lighting of said lamp until sufficient time has elapsed to enable the maximum number of digits in any number to be registered, and operator controlled means for operating said indicating means.

8. In a telephone system, an operator's 5 position, a plurality of lines terminating at said position, the numbers of which include a variable number of digits, a register set comprising sufficient registers to register the number of a called one of said lines 10 containing the maximum number of digits, means controlled by said registers for indicating to the operator any registered number, and a timing device comprising a train of counting relays and an interrupter operable to delay the operation of said means until sufficient time has elapsed to enable the maximum number of digits in any number 15 to be registered.

9. In a telephone system, an operator's 20 position, a plurality of lines terminating at said position, the numbers of which include

a variable number of digits, a register set comprising sufficient registers to register the number of a called one of said lines containing the maximum number of digits, 55 means controlled by said registers for indicating to the operator any registered number, and a timing device comprising a train of counting relays and an interrupter operable to delay the operation of said means 60 until sufficient time has elapsed to enable the maximum number of digits in any number to be registered, said relays being connected in circuits such that said relays are operated by said interrupter in succession 65 and repeatedly.

10. In a telephone system, a timing device comprising an impulser, a train of timing relays, a circuit including said impulser and the relays in succession whereby the relays operate through a plurality of cycles to measure off substantially uniform time intervals, a signaling device and means operated by said last relay in the train at the end of said plurality of cycles for operating 70 said signaling device.

11. In a telephone system, an operator's position, a plurality of lines terminating at said position, a calling line, means for establishing a connection with a desired one 80 of said called lines including a plug-ended trunk circuit at said operator's position, a signaling device at said position, a timing device operable following the restoration of the called subscriber's receiver to its switch-hook, and means operable by said timing device to operate said signaling device if the calling subscriber delays in hanging up his receiver.

12. In a telephone system, an operator's 90 position, a plurality of lines terminating at said position, a register set comprising sufficient registers to register the number of a called one of said lines, means for setting said registers in succession, a progress lamp, 95 and means for lighting said lamp if an undue delay occurs in the setting of said registers.

In witness whereof, I hereunto subscribe my name this 21 day of November, A. D. 100 1923.

ALBERT C. POWELL.
